Patented May 13, 1913

UNITED STATES PATENT OFFICE.

WILLIAM EDWARD POST, OF MANSFIELD, OHIO.

WRENCH.

1,061,925.

Specification of Letters Patent. Patented May 13, 1913.

Application filed July 22, 1912. Serial No. 710,891.

To all whom it may concern:

Be it known that I, WILLIAM E. POST, a citizen of the United States, and a resident of Mansfield, in the county of Richland and State of Ohio, have invented a new and Improved Wrench, of which the following is a full, clear, and exact description.

My invention relates to a wrench comprising a novel arrangement of wrench jaws and handle with means for adjusting the movable jaw of the wrench.

The invention will be more particularly explained in the specific description hereinafter to be given.

Reference is to be had to the accompanying drawings forming a part of this specification, in which similar characters of reference indicate corresponding parts in all the views.

Figure 1 is a side elevation of a wrench embodying my invention; Fig. 2 is a similar view at the opposite side of the wrench; Fig. 3 is an edge view; Fig. 4 is an enlarged detail sectional view showing the adjusting means for the movable wrench jaw; Fig. 5 is a cross sectional view of the elements shown in Fig. 4; and Figs. 6 and 7 are detail views showing the manner of pivoting the detachable element of the pliers.

In constructing the wrench in accordance with my invention, an elongated handle 10 is formed at one end with a fixed wrench jaw 11, which preferably is disposed at an angle to the longitudinal axis of the handle 10.

Co-acting with the fixed jaw 11 is a movable jaw 12, the base 13 of which is disposed at approximately a right angle to the jaw proper and is guided on the fixed jaw. Thus the fixed jaw has a transverse slot therethrough, in which the base of the jaw 12 slides, and one jaw is formed with ribs 14, these being, in the example shown, formed on the inner walls of the slot formed in the fixed jaw; the movable jaw has recesses 15 corresponding with and receiving the said ribs. The lower side of the base 13 of the movable jaw is formed with teeth 16, and a locking block 17 is formed with teeth 18 to engage the teeth 16 of the movable jaw. The said locking block has movement toward and from the movable jaw in a recess 19 formed in the wrench at the base of the fixed jaw. A spring 20 is seated in the bottom of the recess 19 and bears against the under side of the locking block 17, the spring preferably being a plate spring in

arched form, and projecting into a notch 21 at the under side of the locking block.

A bolt 22 passes through the sides of a fixed portion of the wrench head at the base 60 of the jaws, and passes also through the locking block 17. The fixed portion of the wrench is slotted at opposite sides, as at 23, 24, at the points where the ends of the bolt 22 project, the arrangement being such that 65 the locking block 17 with the bolt 22 may move on the fixed portion of the wrench relatively to the base 13 of the movable jaw 12 in an outward direction, under the influence of the spring 20, or in the reverse 70 direction away from the movable jaw when the operator grasps the bolt by its ends to overcome the pressure of the said spring. The bolt head 25 is received in the slot 23, and adjacent to said slot and at the side of 75 the recess 19 in which the locking block is fitted, a retaining plate 26 is detachably secured to the wrench, as by screws 27, the said plate 26 serving to prevent lateral displacement of the locking block. The mentioned retaining plate has an opening 28 at the center, of non-circular form, and the bolt head 25 is of non-circular form and of a less size than the opening 28, so that the recess permits the movement of the locking block and the bolt to and from the fixed 80 jaw, and the arrangement furthermore is such that the bolt head is prevented from turning. The opposite end of the bolt 22 receives a nut 29, said nut being non-circular for at least a portion of its outer edge, and adapted to be received in a recess 90 formed in the fixed portion of the wrench, as shown clearly in Fig. 1. The bolt 22 furthermore is capable of movement axially, 95 and surrounding the shank of the bolt beneath the head 25 is a coil spring 31 which is accommodated in a recess 32 in the side of the locking block 17.

With the described construction the bolt 100 may be grasped at the ends by the operator and moved axially in a direction to overcome the pressure of the spring 31, which spring normally tends to maintain the bolt with the non-circular nut 29 within the non-circular recess 30, but the operator may upon compressing the spring and moving the bolt axially, then move it in a direction away from the movable jaw to withdraw the teeth 18 of the locking block 17 out of engagement with the teeth 16 of the movable jaw, whereupon said jaw may be shifted to 110

adjust its relation to the fixed jaw 11. Upon the operator releasing the bolt 22, the plate spring 20 at the back of the locking block 17 will throw the said block and the bolt 22 in the direction of the fixed jaw, engaging the locking block with said jaw, following which movement the expansion spring 31 will move the bolt axially and return the nut 29 thereon into its recess 30, thereby acting to prevent any retrograde movement of the locking block, and thus maintaining the movable jaw in locked adjustment.

At the end of the handle 10 opposite the described wrench jaws, the handle is formed with a plier jaw 33 that co-operates with the movable jaw 34 of the pliers, the jaw 34 being formed integrally with an element 35 fashioned after the manner of one of the handles of known pliers. The handled element 35 has detachable pivotal engagement with the handle 10, adjacent to the fixed jaw 33 of the pliers, the connection being effected as follows: In the element 35 a slot or opening 36 is formed, the preferred construction having two of such openings, as shown, either one of which may be passed over a T-head 37 formed on a bolt 38. The bolt 38 passes also through a hole 39 in the handle 10, said hole being non-circular, and the corresponding portion of the bolt 38 being similarly formed to prevent the rotation of the bolt relatively to the handle 10. The bolt is held in place by a nut 40. The arrangement referred to is such that to apply the element 35 the latter is turned to a position to bring its slot 36 parallel with the head 37 of the bolt, and pass over said head, after which the element 35 is given a turn to approximately ninety degrees to bring the slot 36 and head 37 at approximately right angles to each other, in which position the jaw 34 of the pliers formed on the element 35 is approximately parallel with the fixed jaw 33 of the pliers, and from which position the element 35 may be oscillated to close or open the jaws of the pliers, without bringing the slot 36 and head 37 into alinement. The jaws 33, 34, at a point between the pivot and the outer ends of said jaws, are formed respectively with nippers 41, 42. When the pliers are not required for use, the element 35 is held in fixed relation to the handle 10 by a spring hook 43, the hooked

ends of which enter holes 44, 45 formed respectively in the wrench handle 10 and in 55 the element 35 of the pliers. The inner end of the element 35 is tapered and formed into a screw driver 46, which may be utilized by detaching the element 35 from the wrench handle 10.

Having thus described my invention, I claim as new and desire to secure by Letters Patent:

1. A wrench, comprising a handle having a jaw, a second jaw movable relatively to the 65 first-mentioned jaw and provided with a base at approximately right angles to said movable jaw, the base having teeth at the under side thereof, the wrench having in the fixed portion back of the movable jaw a recess, a locking block movable in said recess toward and from the movable jaw and having teeth to engage with the teeth of said jaw, a spring normally tending to move the block in the direction of the movable jaw, 70 a bolt passing through the fixed side portion of the wrench, and through the said locking block, the said bolt having a non-circular element at an end thereof, the wrench having a non-circular recess 80 accommodating said element, said bolt being movable axially to withdraw the mentioned element from its recess, the bolt being provided with a spring normally tending to maintain the mentioned element in its recess, and a 85 detachable retaining plate on the fixed portion of the wrench outside of the locking block and its recess.

2. In a wrench, a fixed and a movable jaw, a locking block movable on the fixed portion 90 of the wrench and into engagement with the movable jaw, a securing bolt passing through said locking block and removable therewith toward and from the movable jaw, said bolt being movable axially and serving 95 in one position to prevent movement of the locking block, and in the other position permitting the movement of said locking block.

In testimony whereof, I have signed my name to this specification in the presence of 100 two subscribing witnesses.

WILLIAM EDWARD POST.
